UNITED STATES PATENT OFFICE.

NICHOLAS J. JEFFRIES, OF ATLANTIC CITY, NEW JERSEY.

BINDING-POST.

1,146,881.

Specification of Letters Patent.

Patented July 20, 1915.

Application filed March 25, 1914. Serial No. 827,145.

To all whom it may concern:

Be it known that I, NICHOLAS J. JEFFRIES, a citizen of the United States of America, and resident of Atlantic City, county of Atlantic, State of New Jersey, have invented certain new and useful Improvements in Binding-Posts, of which the following is a specification.

This invention relates to certain new and useful improvements in binding posts and devices of that general character employed for clamping or holding a wire in all forms of electrical or other work.

As is well known, it is a difficult matter generally in affixing a wire or wires by means of the binding posts now in use in which the wire is generally clamped between two nuts upon a bolt. Aside from difficulty and inconvenience in applying and clamping the wire, there is danger of shunting or short circuiting and also great liability of the wire becoming disengaged from the clamp.

It is the object of the present invention to overcome these difficulties, and this in a simple manner embodying a bolt or post, cheap of manufacture and embodying ease of application and security and efficiency in operation.

Other objects and advantages of the invention will hereinafter appear and the novel features thereof will be particularly pointed out in the appended claim.

The invention is clearly illustrated in the accompanying drawings, which, with the numerals of reference marked thereon, form a part of this specification, and in which—

Figure 1 is a face view of a switch plate showing the application of my invention. Fig. 2 is a vertical section on the line 2—2 of Fig. 1 looking in the direction of the arrows. Fig. 3 is a substantially central longitudinal section through the binding post with its cap in position. Fig. 4 is a detail in longitudinal section on the line 4—4 of Fig. 3 looking in the direction of the arrows. Fig. 5 is a horizontal section on the line 5—5 of Fig. 3 looking in the direction of the arrows. Fig. 6 is a view similar to Fig. 3 showing a slightly modified form. Fig. 7 is a cross section on the line 7—7 of Fig. 6 looking in the direction of the arrows.

Like numerals of reference indicate like parts throughout the different views.

The invention is capable of embodiment

in a variety of forms, some of the most efficient of which only are herein shown by the way of illustration.

Referring to the drawings, 1 designates a bolt provided with a preferably axial bore 2 for the passage and reception of the wire and a cavity 3 in the head 4, which latter is exteriorly threaded, as at 5, for the reception of the cap nut 6, which latter has an interiorly screw-threaded depending flange 7 engaging the threads 5 of the head of the bolt. The head of the bolt is provided with a transverse slot 8 which extends into the cavity 3, as seen in Figs. 4 and 5, which slot 70 is designed for the reception of a screw driver or other implement by which the bolt may be screwed into place.

In use the bolt is screwed or otherwise passed through an opening 9 in the switch plate 10 or other article or support to which it may be desired to apply the wire and the wire 11 has its bared portion 12 passed longitudinally into and through the bore 2 of the bolt and the end thereof bent into the cavity 3 or into the slot 8 of the head of the bolt and then the cap 6 is screwed down, firmly holding the wire in place and covering the cavity and the slot of the head of the bolt making a neat finish, as will be understood upon reference to the various figures of the drawing. A nut 13 may or may not be employed upon the bolt, such nut being shown in Figs. 2 and 3.

It will be seen that the slot 8 may be made to serve the double purpose of receiving the screw driver or other implement by which the bolt may be screwed into place prior to the fastening of the wire, and then to receive the bent end of the wire, if desired, as seen in Fig. 2. It is evident that the wire may be coiled about in the cavity 3 or, if desired, it may be soldered in place.

In Figs. 6 and 7 I have shown a form designed for use in a material other than wood, as, for instance, in marble. In this form the bolt 1 has the axial bore 2, the cavity 3 and the slot 8 for the reception of a screw driver, the head 4 being screw-threaded, as at 5, and receiving the threads 105 of the flange 7 of the cap 6, as before. The head is provided, however, upon its under surface with projections or the like 14 which may be of greater or less number and the purpose of which is to embed themselves in the marble or other material so as to prevent rotation of the bolt, it being un-

derstood that these are to be employed when the bolt is used in connection with marble or such other material where the bolt cannot be screwed into place. In such instances the bolt need not be provided with the screw threads, except at the end, a nut 13 being applied to the threaded end of the bolt and adapted to bear against the under side of the marble or other support through which the bolt passes.

The mode of use will be apparent and the advantages of the invention will be readily understood from the foregoing description when taken in connection with the annexed drawings, particularly Figs. 1 and 2, wherein the wire is shown as passed upward through the bore of the bolt and the end fastened within the cavity or slot of the head of the bolt and there retained and concealed by the cap. This serves to hold the wire securely in position, provides for easy application and attachment of the wire and also for ready displacement when desired by simply unscrewing the cap and disengaging the end of the wire when the

latter may be readily pulled through the bore of the bolt.

Modifications in detail may be resorted to without departing from the spirit of the invention or sacrificing any of its advantages. 30

What is claimed as new is:—

An exteriorly threaded bolt having an axial bore and having at one end a shoul- 35 dered head with a cavity in the outer face of the head surrounding said bore and com- municating therewith and a slot extending radially in the outer face of said head from said cavity to receive a screw driver, said cavity and slot adapted to receive the lat- 40 erally bent end of a wire inserted through said bore, and a removable cap engageable with said head and extended over and cov- ering said cavity, slot and bent end of the wire.

Signed my me at Washington, D. C., this 45
25th day of March, 1914.

NICHOLAS J. JEFFRIES.
